CLAIM

The ornamental design for a combined baseball device and drinking vessel surface, as shown and described.

DESCRIPTION

FIG. 1 is a perspective view of a first embodiment of a combined baseball device and drinking vessel surface showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view showing a second embodiment of the combined baseball device and drinking vessel surface;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines in the drawing views depict environment that forms no part of the claimed design. The dot dash broken lines illustrate a boundary that forms no part of the claimed design.

1 Claim, 10 Drawing Sheets
